OSCILLATION GENERATOR

Wilhelm Runge, Berlin, Germany, assignor to
Telefunken Gesellschaft für Drahtlose Tele-
graphie m. b. H., Berlin, Germany, a cor-
poration of Germany

Application October 28, 1929, Serial No. 402,962
In Germany November 2, 1928

5 Claims. (Cl. 250—36)

This invention relates to oscillation generation and particularly to a regeneratively connected thermionic tube for producing continuous waves, in combination with a mechanical oscillating system coupled to the tube for frequency stabilization purposes.

It is known to be possible to create, by means of mechanical oscillating systems, frequency standards which surpass in constancy all electrical oscillation circuits as to the order of magnitude. In selecting materials suitable for such frequency standards it is, however, important to ascertain that the materials possess qualities which would make possible to interconnect the mechanical and electrical processes. On account of this condition only piezo-electric materials, such as quartz, and magnetic materials, such as steel, have been applied in the prior art for frequency standards. Owing to these electro-mechanical qualities such a system in accordance with my invention may be regeneratively coupled over thermionic tubes and used as a transmitter of a normal frequency.

The required piezo-electric or magnetic quality limits the number of materials suitable for frequency standards. Quartz has a high temperature coefficient with the result that the frequency varies rapidly with the temperature and steel displays frequently evidence of fatigue and of time-modifications caused by recrystallization. Other materials, although mechanically qualified, have so far not been applicable as frequency standards on account of the impossibility to transfer their mechanical actions into electrical actions. According to this invention, such a transfer of mechanical into electrical effects, and vice versa, is obtained by making use of the dielectric qualities of insulators and of the conductivity of conducting materials. Thus one is not limited in the least in the choice of materials. It is, for instance, possible to use now fused quartz, the temperature coefficient of which is considerably lower than that of crystalline quartz and which is practically obtainable in pieces of any size, although the material possesses no piezo-electric qualities. Conversion of the mechanical processes into electrical processes may be effected, by way of example, according to the apparatus shown in the drawing in which:

Fig. 1 illustrates one preferred embodiment of the invention; and

Fig. 2 illustrates a modification thereof.

In Fig. 1, the rod 1, made of dielectric material, for example fused quartz, is to be made to

oscillate longitudinally in the fundamental wave. To attain this the middle of the rod is placed between two electrodes 2, 2 which are connected across a source of constant potential (battery) 3 and a resistance 4. The grid-filament circuit of a thermionic tube 5 is connected in parallel with the resistance 4. The two ends of the rod project beyond two metal rings, one of which (6) is connected to one terminal of the battery 3, the other (7) by way of an oscillating circuit 8, to the other terminal of the battery 3. The battery 3 serves at the same time as a source for the plate potential of the thermionic tube. With this circuit arrangement the following process takes place:

Let us assume that the rod oscillates already on its fundamental wave. This causes considerable compression and tension in the middle of the rod, with accompanying changing of the dielectric constant of the rod corresponding to its change in volume in this part. Hence, the capacity between the electrodes 2, 2 is changing in synchronism with the oscillations of the rod. Since the battery 3 maintains a constant potential, the current flowing in the circuit comprising battery 3, resistance 4, and capacity 2, 2, is an alternating current which causes at the resistance a potential drop the frequency of which is equal to that of the rod. This alternating potential controls, in a manner well known in the prior art, the plate current in the thermionic tube 5 and creates thereby an alternating potential in the oscillation circuit 8 resulting in an alternating potential component between the rings 7 and 6 which are already supplied with a constant potential from the battery 3. The electric field between these two electrodes partially travels through the dielectric material of the rod, generating in it a force which causes the rod to contract. If the potential between the rings 7 and 6 changes periodically, the rod is subjected, in addition to the constant contraction attributable to the action of the constant potential, to an alternately compressing and tensile force which, with a properly adjusted phase, maintains the mechanical oscillations. The proper phase may be obtained by selecting a proper phase angle for the resistance 4, proper polarity of the couplings 8, 9, and by tuning 8. The energy lost on account of internal friction in the rod is therefore replaced by the thermionic tube 5. The rod oscillates like an undamped transmitter.

If the rod is not made of a dielectric material but of a conducting material the regenerative coupling may be accomplished according to Fig. 2. Two electrodes, 12 and 13, connected across a coil

14 and battery 15, are facing one end of the rod 20 which is assumed to be oscillating longitudinally in its fundamental wave. The coil 14 is coupled with a circuit 16 which is connected to the grid-filament circuit of a thermionic tube 17. A branch of the coil 14, preferably the center, is connected to the filament of the tube 17. From the filament of the tube 17 a lead extends by way of the plate potential battery 18 and an oscillating circuit 19 to the electrode 10 which faces the other end of the rod. The plate of the tube 17 is connected to the plate potential battery 18 by way of a coil 11, coupled with the circuit 19. The action of this circuit arrangement is as follows: A longitudinal oscillation of the rod causes a periodical changing of the distance between the electrodes 12, 13 and the left end of the rod 20. The capacity between the electrode 12 and the rod 20 and between the electrode 13 and the rod 20 will vary accordingly, and so will the capacity resulting from the series connection of the two capacities. The battery 15 maintains this resultant capacity at a constant potential. A variation of the two component capacities will therefore cause an alternating current to flow in the circuit 12, 20, 13, 15, 14. This alternating current induces a potential in the circuit 16 which is supplied to the grid of the tube 17. The resulting alternating plate current of the tube 17 induces an alternating potential in the circuit 19 which becomes superposed upon the direct current potential maintained between the electrodes 12, 13 and the electrode 10 by the battery 18. The electrostatic forces between 12, 13 on the one hand and 20 on the other, and between 10 on the one hand and 20 on the other, which cause tension in the rod, are thus periodical-ly increased and diminished in intensity. With a proper phase selection, that is with the tuning of the circuits 19 and 16, these forces act in such a manner as to maintain the existing oscillations.

In either of the above circuit arrangements a thermionic tube is used to maintain the oscillations of a mechanical system. At any point of the thermionic tube, such as at the plate lead, alternating current energy may be taken out, the frequency of which would be determined by the natural frequency of the oscillating system. Hence, the described arrangements may also be utilized to generate alternating currents.

Although the described circuit arrangements show only one thermionic tube it is in many instances advisable to employ an amplifier in the form of several cascade-arranged tubes, the first grid being supplied with the oscillating potential caused by the mechanical oscillating system and the last plate lead supplying the energy which is to be fed back to the oscillating system. The advantage of employing several cascade arranged amplifying stages as compared to one single tube consists in the fact that owing to the much greater amplification, the couplings between the oscillating system and the amplifying system may be considerably looser. If, for instance, an amplifier of several cascade-arranged tubes were employed instead of the tube 17 in Fig. 2 it would be possible to increase the distance between the electrodes 12, 13 and the end of the rod, and the distance between the electrode 10 and the end of the rod. This would result in a diminution of the reactions which the electrodes with their circuits exert on the natural frequency of the mechanical system.

What I claim is:

1. In a system for producing oscillations, an electron discharge device having input and output circuits, said device acting to amplify electrical oscillations applied to the input circuit thereof, a condenser arrangement comprising two capacities, one capacity being connected across said input circuit and the other capacity being inductively coupled across at least a portion of said output circuit, and a common vibratory body between the armatures of said two capacities, a constant source of potential across the armatures of said two capacities for creating an electric field across said armatures and through said vibratory body, said vibratory body being arranged when in a state of oscillation to produce a variation in potential across the armatures of that capacity which is connected across said input circuit for varying the potential of said input circuit, said variation in potential being amplified by said device to cause a variation in potential across said other capacity. 10 15 20

2. In a regenerative system for producing oscillations, an electron discharge device having input and output circuits, a condenser arrangement comprising a vibrating rod-like element vibrating longitudinally of its fundamental wave, a plurality of armatures at one end of said element, a single armature at the opposite end of said element, a coil in said input circuit, a second coil across said plurality of armatures and inductively coupled to said first coil, a third coil in said output circuit, and a fourth coil connected to said single armature in circuit with said first coil and in inductive relation to said third coil, said vibratory element when oscillating being arranged to vary the capacity between said single armature and said other armatures. 25 30 35

3. In a system for producing oscillations having, in combination, an electron discharge device, input and output circuits for said device, a condenser arrangement for coupling said input and output circuits comprising a single mechanically vibrating element, two armatures at substantially the opposite ends of said element, a circuit including 40 45 an inductance and a source of potential connected between said last two armatures, said inductance being inductively coupled to said output circuit, said source of potential also being in said output circuit, and two armatures intermediate the ends of said element and separated thereby connected across said input circuit, said element being common to said four armatures. 50

4. A system for producing oscillations having, in combination, an electron discharge device, input and output circuits, means for biasing the grid of said electron discharge device, means for varying the potential across said input circuit comprising a condenser having fused quartz for a dielectric, a plurality of armatures for said condenser, at least two of which are coupled to said input circuit, and a connection coupling at least one other armature of said condenser with said output circuit, and a source of potential in said output circuit directly connected to said last armature. 55 60 65

5. A system in accordance with claim 2, characterized in this that said vibratory element comprises electrical conducting material. 70
